Primary Examiner—Celia Murphy[57] CLAIM

The ornamental design for a vest, as shown and described.

DESCRIPTION

FIG. 1 is a perspective view of a vest showing my new design, the broken lines shown throughout the views being understood to represent stitching;

FIG. 2 is a front elevation view thereof;

FIG. 3 is a right side elevational view thereof; the left side being a mirror image thereof;

FIG. 4 is a rear elevation view thereof;

FIG. 5 is a top view thereof; and,

FIG. 6 is a bottom view thereof.
